MINE ROOF TESTING

Robert T. Gallagher, Bethlehem, Pa., Cornelius G. Brennecke, Raleigh, N. C., and Robert D. Currie, Trucksville, Pa., assignors to General Reinsurance Corporation, New York, N. Y., a corporation of New York

Application October 25, 1945, Serial No. 624,358

3 Claims. (Cl. 73—67)

1

This invention relates to mine safety apparatus and methods. More specifically, the invention comprises apparatus and methods for testing the strength of the rock structure of mine roofs, in order to identify unsafe rock areas before roof falls occur.

Despite efforts taken to reduce mine accidents and fatalities, mine roof falls still account for approximately 60% of the total underground fatalities in coal mines. In other words, over 1,000 miners are killed and more than 15,000 are seriously injured by mine roof falls each year. This results from the fact that the majority of mine workers are employed at the mining face where new roof material of unknown strength is continually being exposed.

The method which for generations has been employed for testing the rock structure of mine roofs and which is still in general use, comprises striking the roof a sharp blow with a tool such as a miner's bar or a hand hammer and listening to the resulting sound waves emanating from the roof material. The character of the resulting sound is then interpreted as indicating solid or loose rock. One difficulty with this method is that the sound produced by the ring of the metal bar or hammer may obscure the sound from the roof rock. Although this test is the one most generally employed, it is so unreliable that mine workers frequently disagree as to the roof condition thus indicated. The only sure test of a roof by this method is possible in the event that the roof material comprises a relatively thin piece of rock which has drawn away from the main roof to form a pocket enclosing air or gas. The sound emitted from the striking of such a formation results in a drummy sound readily identified as an unsafe roof, and in this case appropriate props are customarily employed. However, many equally unsafe roofs result from different formations which do not produce sounds capable of identification, as where the roof material is irregular in shape or thickness, or where a crack or crevice is at an angle to the main roof, so that the vibrations are not reflected back to the ears of the tester, or the sounds are not distinguishable from those emanating from safe rock.

Another method for determining the condition of the roof rock includes striking the rock to produce vibrations therein and perceiving the vibrations by touching the fingers to the rock. Occasionally loose rock can be thus detected if it is small enough and sufficiently loose to vibrate and, of course, if the fingertips of the operator are

5 sufficiently sensitive and he is thoroughly experienced in the technique. Additional methods heretofore employed in determining the strength of mine roofs include visual inspection for slips, flaws, inclusions or change in strata material, and in the interpretation of these observations by one highly skilled as the result of long study and experience. Although the records of accidents due to falling mine roofs, especially in coal mines, have stimulated investigation and research directed toward lessening such accidents, no method or apparatus resulting in any substantial improvement has been proposed for many years.

10 The apparatus and method according to the present invention make possible for the first time the testing of the rock structure of mine roofs with such a high degree of sensitivity and accuracy that unsafe roof conditions can easily be recognized by even unskilled workers with great reliability. As a result of actual experience in coal mines it has been found that unsafe roof conditions can readily be determined by means of this invention, and appropriate measures taken to prevent roof falls under circumstances where

15 previous testing techniques would indicate the roof to be safe.

20 Briefly, the present invention comprises, first, striking the mine roof a single blow, preferably with a constant blow hammer, to generate a compression-wave train of free oscillations of a certain amplitude in an area of known rock characteristics, electrically measuring the effective amplitude of this compression wave train at a detection point in this first area, similarly generating another compression wave train of substantially the same amplitude in an adjacent area of unknown rock characteristics, electrically measuring the effective amplitude of the second compression wave train at effectively the same detection point, and comparing the two measurements. If the measurements are substantially the same it may be assumed that the rock between the two areas is substantially uniform, whereas if the second measurement is considerably lower than the first the indication is that unsafe rock exists between the two locations or test stations where the compression waves were generated. By "closing in" on the low-indication area, the boundaries of unsafe rock can quickly be ascertained. This procedure can most effectively be carried out by including compensation for the attenuation in compression wave transmission through the rock resulting from the various distances which the compression waves

25 30 35 40 45 50 55 must travel from the testing stations where the

blows are struck to the detecting point where the waves are detected.

The apparatus necessary to carry out the testing procedure above outlined should be rugged and portable. Suitable equipment includes a hammer, preferably of the constant blow type, to generate the compression waves in the rock, a pickup device to detect the waves and transform them into electrical vibrations, a suitable electrical amplifier energized by the pickup, and an indicating device actuated by the output of the amplifier for indicating measurements of the amplitudes of the detected waves. The amplifier may include a compensator for the purpose above mentioned.

A more complete understanding of the invention will be had from the following specification considered in connection with the accompanying drawings, wherein:

Fig. 1 illustrates the apparatus in accordance with the invention as employed in testing a roof in a coal mine;

Fig. 2 is a circuit diagram of the electrical apparatus employed in accordance with the invention;

Fig. 3 is a plan view of an assembly of a constant blow manner which may be used in connection with the invention;

Fig. 4 is a longitudinal central cross sectional view of the hammer of Fig. 3;

Fig. 5 is a cross sectional view of the hammer taken along the line 5—5 of Fig. 3; and

Fig. 6 is a cross sectional view of the hammer taken along the line 6—6 of Fig. 4.

In Fig. 1 a section of a coal mine is represented as having a roof 1, shown partly in section exposing strata or layers 29, 30, 31, 32, 33, 34, supported at intervals by pillars 2. These pillars divide the mine proper into chambers 20 and gangways 21 which may be of various dimensions depending somewhat upon the nature of the rock and coal structures in the particular mine. Usually the pillars alone are not sufficient to support the roofs of the chambers, so that wooden props are customarily employed at intervals to hold the roof from collapsing. In order to simplify the drawing, such props are not shown in the illustration. It will be evident, however, that the use of props is undesirable because they entail time and expense to erect and greatly interfere with communications and traffic within the mine. If the roof structure is strong enough to be self-supporting, props are not required; whereas if the roof is not strong and an insufficient number of props are used there is the constant danger of a roof fall or cave-in, probably resulting in a fatal accident. By means of the present invention, the safety of the roof structure may be quickly ascertained by a foreman or a miner as the cutting exposes new rock, permitting adequate props to be inserted before the roof falls.

Method of mine roof testing

In accordance with the invention, a hole 3 (Fig. 1) is first drilled a foot or so in or adjacent the roof of the mine, preferably horizontally, but in any event at an angle such that the pickup device will respond satisfactorily to the compression wave energy to be detected. The type of drill customarily used in the mine for drilling dynamite holes is suitable. This hole should be drilled in a rock area of known structure, viz., known to be satisfactorily strong and safe against roof falls. Into this hole is inserted a detector or pickup device 4 which is described below in

more detail. Such devices are sometimes referred to as "geophones." The geophone 4 is electrically connected by a suitable length of insulated cable 6, say 100 feet or more, to the amplifier box 5 preferably containing the remainder of the electrical apparatus, and which includes the mentioned amplifier, the necessary controls, and the meter or indicating device which is actuated by the output current from the amplifier and which should be observable on the exterior of the box 5.

The compensator having previously been calibrated to suit the characteristics of the rock, as explained below in connection with Fig. 2, it should be set at the first or 25 foot setting of the device. The operator may then take up a position at a test station, such as the point marked "A" in Fig. 1 near the location 3 of the geophone. The roof rock in the general vicinity of station "A" should be of known strength. If then, a hammer blow is struck on the roof rock at test station "A" the indicator on apparatus 5 should give a maximum, or approximately maximum, reading. If it does not, the volume control included as a part of the amplifier equipment can be adjusted to provide an approximately maximum reading on the meter.

For purposes of explanation it may be assumed that at this time the chamber 20 has been mined to a point only slightly beyond station "B" shown in Fig. 1. In this event the distance from station "A" to station "B" might be, say, 25 feet. Therefore, in order to test the safety of the newly exposed mine roof, the operator will proceed to the new station and repeat the operation above described, viz., at test station "B" he will leave the compensator set at 25 feet and will then strike the roof rock with a hammer blow of a force substantially equal to that of the blow struck at station "A", at the same time observing the measurement indicated on the meter. If the rock in the area between station "B" and detection point 3 is of uniform structure, and substantially the same as that between point 3 and station "A", the meter reading at station "B" will be substantially the same as at station "A". On the other hand, if loose rock or other structural defect in the roof material intervenes between point 3 and station "B", the meter reading will be considerably less than that at station "A", in which event suitable props may be placed to support the roof with safety.

The area of the unsafe portion of the roof may be more closely located by proceeding backwards from station "B" toward station "A", or toward pickup point 3, by one or more paths, striking similar hammer blows at intervals of a few feet each, and observing the meter reading at each new testing station. By this means of "closing in" on the unsafe area, a reasonably accurate outline of the unsafe area may be determined in a very short time.

As the mining continues to lengthen chamber 20, additional tests at stations as indicated at "C" and "D", or at closer intervals, may be made. In the drawing, an operator is represented at station "C" holding a constant blow hammer against the surface of the roof rock while observing the indicating device on the box 5 suspended on a strap around his neck, he having previously set the calibrator to the 50-foot point. The cable 6 here assumed to be of somewhat more than 100 feet in length will permit the operator to proceed at least as far as station "E" before removing the geophone 4 from hole 3 and reinserting it in a new hole 3'. After inserting the

geophone in hole 3' the operator might start the new series of tests at or near station "E" as a known basis and then proceed to unknown station "F". After adjusting the compensator to suit the distance between station "F" and point 3', he would proceed as before, always working from a rock area of known strength and safety to an area of unknown strength. In order to insure tests of greatest accuracy the operator should always set the compensator to a point most closely corresponding to the distance between the geophone 4 and the test station at which the hammer blow is struck.

The procedure above described can readily be carried out by a single operator. However, it will be clear that the same result may be achieved by employing two men, one of whom remains at the location of the indicating device and the other of whom proceeds to the successive test stations with the hammer. While such procedure is entirely feasible it sometimes is undesirable because it requires communication between the hammer man and the instrument man, which is difficult or inconvenient when the mine is being worked.

Apparatus

The detector or pickup device 4 herein termed the geophone is an electro-mechanical transducer which transforms mechanical wave energy into electrical vibrations or wave energy. Such a device of the piezo-electric or crystal type has been found especially successful in connection with the present invention. This crystal pickup device may be suitably mounted in a closed cartridge of heavy metal, such as brass, shaped to fit hole 3, and might be 1 1/4 inches in diameter by 8 inches long. Inasmuch as the vibrations to be detected travel horizontally, in general, the greatest response is attained if the crystal is mounted in the cartridge so as to be effectively horizontal when used.

The amplifier box 5 shown in Fig. 1 preferably contains the remainder of the electrical apparatus which is connected to the geophone 4 by a suitable cable 6. It is very desirable that the equipment comprising amplifier box 5 be compact and of light weight because it must usually be carried considerable distances through a mine where walking is difficult and arduous. By the use of vacuum tubes of the hearing aid type, energized by dry batteries of the hearing aid or similar compact type, and by judicious selection of components known in the art, a suitable amplifier may be constructed which will meet the requirements above outlined. The amplifier box is preferably arranged to be suspended on a strap to be hung around the test man's neck or waist so that the necessary controls and indicating meter mounted on the exterior of the box may be accessible for observation and manipulation, as required. The circuit arrangement of a suitable amplifier and indicating device is represented in Fig. 2.

The apparatus illustrated in Fig. 2 includes an amplifier comprising three vacuum tubes preferably of the hearing aid type in order to permit the apparatus to be compact and of light weight. In fact, all of the apparatus should preferably be selected with that object in view. Accordingly, vacuum tubes V₁ and V₂ may be of Raytheon type CK510AX and tube V₃ of type CK507AX. The tubes V₁ and V₂ are double tetrodes, resistance-capacity coupled in conventional manner to provide substantially linear

amplification of five stages. The input to tube V₁ is coupled through transformer T₁ to the pickup device or geophone 4. Tube V₃ is a pentode of the power output type. To the output of this tube is connected output resistor R₁₅ to which is connected, through a coupling condenser C₈, a suitable indicating device or meter 22. The meter here represented is a microammeter having a 0 to 50 microampere scale. 10 The meter being a direct-current instrument is connected to a full-wave rectifier of the copper oxide type so that it may indicate alternating current. Other suitable types of indicating devices may, of course, be used. It is sometimes 15 desirable that the output be checked by an oscilloscope or by a telephone receiver. For this purpose a jack (not shown) may be connected across resistor R₁₅, or at any other suitable point in the system in a manner well known in the art. 20 To enable those skilled in the art to construct and use an amplifier in accordance with the invention herein described, values of the various circuit elements as indicated by their reference characters in Fig. 2 are suggested below. It 25 should be understood, however, that the specific circuit arrangements here shown, as well as the values of the elements below listed, are given merely by way of example of one embodiment of the invention.

30	R ₁ —200,000 ohms	C ₁ —.05 mfd.
	R ₂ —2 megohms	C ₂ —.002 mfd.
	R ₃ —5 megohms	C ₃ —.002 mfd.
	R ₄ —2 megohms	C ₄ —.05 mfd.
35	R ₅ —3 megohms	C ₅ —.002 mfd.
	R ₁₀ —200,000 ohms	C ₆ —.002 mfd.
	R ₁₁ —2 megohms	C ₇ —.05 mfd.
	R ₁₂ —5 megohms	C ₈ —.005 mfd.
40	R ₁₃ —2 megohms	R ₁₄ —5 megohms
		R ₁₅ —15,000 ohms

40 In order to simplify the circuit arrangement, a single high voltage or "B" battery 23 is employed by way of compromise. In view of the particular vacuum tubes selected for the amplifier here described a battery of 45 volts may be used. "A" battery 24 of suitable voltage to supply the filaments or cathode heaters may be connected as shown in series with a control switch 28. The opening of switch 28 in the low voltage circuit effectively disconnects both batteries because when the cathodes are unheated the resistances of the anode circuits are so high that the anode circuits to which battery 23 is connected, are effectively on open circuit. Thus, there results no spark sufficient to be dangerous in the presence of mine gases. A voltage dropping resistor 26 is here employed because it happens that the normal filament voltage of tubes V₁ and V₂ is less than that of tube V₃. If the rated filament voltages be the same for all tubes this resistor should be omitted.

60 One feature of the invention which requires description in some detail is the compensator 27. This comprises, as shown, a resistor R₆—R₇—R₈, 65 variable in steps, the effective resistance of the compensator being connected in series between the slider of potentiometer resistor R₅ and the first control grid of vacuum tube V₂. The resistance values of resistors R₆—R₇—R₈ should be chosen in any given instance to suit the characteristics of the rock in the mine in which the equipment is employed. To provide one illustrative example of the order of magnitude which such compensating resistors might have, values 70 are given below. It should be understood, how-

ever, that these values were selected to provide the necessary compensation under the conditions of rock encountered in a particular mine and would necessarily be different were the equipment to be used with rock having considerably different compression wave transmission characteristics.

R₆—2.25 megohms   R₈—.10 megohm
R₇—.25 megohm   R₉—.40 megohm

Calibration of compensator

The calibration of the compensator is effected by giving the resistors R₉, R₈, R₇ and R₆ values such that at each point of switch S₁ the gain of the amplifier will be increased an amount sufficient to compensate for the attenuation in compression wave transmission through the rock between the detection point and each test station as represented respectively by the corresponding contact point on switch S₁. The resistance values of these resistors above given were arrived at empirically as a result of measurements of attenuation of compression waves through the rock of a coal mine, and of the resulting drop in signal output from the amplifier, from which the necessary increase in amplifier gain at the different distances could be determined. The values of the mentioned resistors were selected to provide such gain, keeping in mind that the effect of these resistors on the gain is somewhat interdependent. It is to be noted that in the circuit of Fig. 2, as the switch is advanced from the 25 foot point toward the 100 foot point, the resistance connected between the control grid and cathode of tube V₂ is increased, resulting in a proportionate increase of signal voltage on the grid.

From the foregoing it will be evident that the precalibration of the compensator as above described should be made in advance of the actual testing of roof material in connection with mining operations. However, once the proper values of resistors R₉ to R₆ are determined, the apparatus may readily be calibrated by the operator, by adjustment of R₆, to suit the local conditions under which the tests are to be made.

Such calibration may be as follows: First, an area in the mine must be selected wherein the rock is known to be solid and safe for a distance of, say, 100 feet. Then the geophone 4 is inserted in the rock at one extreme of this distance, and with the switch S₁ set at the 100-foot (or other appropriate) point, a hammer blow is struck at the other extreme of the 100-foot distance. Resistor R₆ (which is adjustable from the exterior of box 5) is then adjusted until a substantially maximum meter reading is obtained. If further check is desired, successive similar hammer blows may be struck at 75, 50 and 25 foot distances, with the switch S₁ set at the corresponding points, respectively. If the hammer blows are all of substantially equal intensity, the meter reading should all be substantially maximum.

The foregoing adjustments effect an increase in gain of the amplifier in steps proportional to the increased attenuation of compression wave transmission through the rock at the different test stations where the hammer blows are struck. The precalibration of the compensating device as above described will usually hold good for many different locations in the same mine, and, indeed, in different mines, without readjustment of the resistors R₆ and R₉. However, it is at times

necessary to readjust the volume control R₅ at the start of the tests so that the indicating meter will read substantially maximum, if the intervening rock is solid.

The compensator having been adjusted and calibrated for approximately specific distances between testing stations, as above described, the indications or readings of the meter 22 will be substantially constant when uniformly solid rock is tested at the various predetermined distances from the geophone. If the testing stations are at positions intermediate to those for which the apparatus is calibrated, viz., say 35 feet when switch S₁ is set for 25 feet, or at, say, 60 feet when the switch S₁ is set for 50 feet, the meter reading will be slightly less than maximum. Such slightly decreased reading will not confuse the operator because if in an actual test of unknown rock a section of soft or otherwise dangerous rock occurs between the test station and the location of the geophone, the increased attenuation will be so marked that the reading on meter 22 will be much lower than the slight decrease of reading due merely to attenuation of a few feet of solid rock. Accordingly, it is possible, and frequently desirable, especially in equipment to be used by unskilled miners, that the dial of the indicating meter 22 be divided and marked in zones labeled "Safe" and "Unsafe", for example. The "safe" zone might cover the area of say the top one-third, or even the top one-half, of the meter scale. Actually the settings of the calibrating device 27 overlap to some extent, i. e., the 25-foot point for switch S₁ might produce satisfactory indications for distances from 0 to 35 feet from the geophone, the 50-foot point being satisfactory for distances of from, say, 20 feet to 55 feet from the geophone, etc. Thus it will be seen that the compensation is not critical, but it becomes nevertheless, increasingly important as the distance from the geophone to the testing station is increased.

In addition to the electrical apparatus above mentioned, the other apparatus required in practicing the present invention is a suitable hammer or other means for striking the roof rock in order to generate sound or compression waves which are to be picked up and recorded. Although such waves may be generated by the impact on the roof rock of any suitable hard object, as mentioned previously, it is preferable that the device be capable of striking successive single blows of uniform intensity. If blows on the roof at successive positions vary greatly in intensity, the indications of the indicating meter will correspondingly vary, from which it may be difficult to ascertain whether the variations in readings are due to variations in intensity of hammer blows or to variations in rock structure between the successive positions. However, it has been found in practice that the hammer blows need not be of exactly uniform intensity because as a rule the variations in rock structure of such nature as are likely to result in a roof fall will result in a considerable decrease in the meter reading, whereas ordinary variations in the intensity of the hammer blows will effect comparatively small changes in the meter readings. However, in order to eliminate one possible source of error, it is preferable that a hammer of the constant blow type, as illustrated in Figs. 3 to 6, inclusive, be employed.

A construction of constant blow hammer found suitable for present purposes is shown in its assembled form in Fig. 3 wherein a metal casing 7,

which may be constructed from a suitable length of heavy iron pipe open at one end 8 and closed by a pipe cap 9 at the other end, encloses a metal plunger 10 (Figs. 4 and 5). This plunger is urged toward the front end 8 by two tension springs 11, one on each side of the plunger. To the back of the plunger 10 is secured a plunger rod 12 terminating in a hand grip 13 by which the plunger may be pulled back against the tension of springs 11. A dog 14 fixed to rod 12 may be engaged with any of the teeth on rack 15 by rotating rod 12 after it has been drawn back to any desired position. Such positions may be predetermined by observing the calibration marks 17, along the outside of casing 7, in their relation to index 16 which is attached to a bolt 18 passing into plunger 10 and extending through a suitable slot 25 on the side of casing 7. Another similar bolt and slot (Fig. 5) are on the opposite side of casing 7.

In use, the hammer is cocked by drawing back handle 13 until index 16 coincides with the calibration line 17 corresponding to the predetermined blow desired. The handle may then be turned to the left to lock the hammer at that predetermined setting. Then when the operator reaches the desired test station where a blow is to be struck, he presses the forward end 8 of the hammer against the rock surface and turns the knob 13 to the right, grasping it loosely enough so that when the plunger 10 is released the force of the springs 11 will pull the handle 13 out of the operator's fingers. Plunger 10 then strikes the rock with a blow of predetermined force, as a result of which a single wave train of free, damped oscillations is generated in the rock. If the hammer is released when the forward end is not against a hard object, such as a rock face, the handle 13 will be drawn against cap 9 with considerable force. A buffer such as spring 19 is therefore interposed on rod 12 between cap 9 and handle 13 to absorb the force of the blow.

What is claimed is:

1. The method of testing a mine roof for safety, which includes creating at a first test station a first single train of damped compression waves in an area of rock of known strength, detecting said waves at a pickup point in rock within said area, measuring the effective amplitude of the detected waves, advancing to a second test station in an area of rock of unknown strength, creating in rock at said second station a second single train of damped compression waves, detecting said second waves at said pickup point, amplifying said second waves to a degree which compensates for the difference in normal attenuation of wave transmission characteristics between said first and second stations, and measuring the effective amplitude of the detected and amplified waves created at said second station, whereby the strength of the unknown rock may be determined by comparison of said measurements.

2. The method of testing a mine roof for safety, which includes striking the mine roof at a first

station with a single blow to create a compression wave train of free oscillations in a limited roof area of known strength, converting said waves into electric waves at a certain point in the rock in said area, amplifying said electric waves and indicating the effective amplitude of said electric waves, advancing from said known area toward a rock area of unknown strength, striking the mine roof at each of a plurality of successive stations separated by approximately equal increments of distance from said point with a single blow of effectively the same intensity to create a compression wave train of free oscillations at each station in succession, increasing the degree of said amplification to compensate for the effective increase in normal attenuation of compression wave transmission in said rock due to the increase of distance between said point and said successive stations, converting said successive waves into electric waves at said point, amplifying said last named waves, and indicating the effective amplitudes of said last named waves whereby they may be compared respectively with the first named indications.

25. 3. The method of testing mine roof rock for safety, which comprises creating a compression wave train in said rock successively at each of a plurality of stations separated increasingly distant from a point in a rock area of known strength, receiving said waves at said point, converting the received waves to form electric waves, amplifying said electric waves, compensating said amplification on the basis of normal attenuation of compression wave transmission in said rock by amplifying the electric waves in proportion to the increase of distance between stations, and indicating said amplified waves, whereby to ascertain the relative strength of the rock between said successive stations.
